(57) **CLAIM**

The ornamental design for a door casing, as shown and described.

DESCRIPTION

FIG. 1 is a right front perspective view of the inwardly directed surface of a door casing for a vehicle according to the present invention.

FIG. 2 is a rear left perspective view of the outwardly directed surface of the door casing shown in FIG. 1.

FIG. 3 is a front view of the door casing shown in FIG. 1.

FIG. 4 is a rear view thereof.

FIG. 5 is a right side view thereof.

FIG. 6 is a left side view thereof.

FIG. 7 is a top view thereof.

FIG. 8 is right front perspective view of the inwardly directed surface of a door casing for a vehicle, similar to FIG. 1, but directed to another embodiment of the invention; and,

FIG. 9 is a rear left perspective view of the outwardly directed surface of the door casing shown in FIG. 8.

In FIGS. 8 and 9 the broken dash lines comprise claim boundaries and neither the portions inside the broken dash lines nor the broken dash lines themselves form any part of the claimed invention.
